UNITED STATES PATENT OFFICE

WALTER EVERETT MOLINS, OF DEPTFORD, LONDON, ENGLAND

CIGARETTE-MAKING MACHINERY

Application filed December 2, 1926, Serial No. 152,295, and in Great Britain December 18, 1925.

This invention is for improvements in or relating to cigarette making machinery and more particularly to a cigarette making machine of the continuous rod type, and has for its object the provision of mechanism adapted for use in severing an axially moving rod into lengths so as to ensure that the ends of the severed lengths are normal to the axes thereof.

10 It has been proposed to provide a rotary ledger plate in connection with cutting mechanism for severing an axially moving rod into lengths wherein the plate is arranged to rotate in a horizontal plane which extends through the axis of the moving rod. Ledger plates of the above character are provided with a semi-circular groove in their rim which is adapted to receive the moving rod and one or more radial slots are cut in the rim so

20 as to receive a movable cutting blade.

It has been found however, with ledger plates of the above character, that due to the fact that the axially moving rod engages with a radially disposed surface of the plate and the edge of the blade engages with a radially disposed slot, the different speeds of the radial points along the surface of the groove and the slot, impart to the sections of the moving rod a gradually decreasing speed

25 which causes the ends of the rod to receive an inclined cut which is detrimental.

In order to obviate this difficulty, it is proposed, according to the present invention, to provide a rotary ledger plate wherein the

30 surface thereof which is adapted to support the moving rod during the cutting operation is arranged so that all the points on the surface which support the rod, travel at the same speed as the rod and a transverse slot or slots formed in the said surface is arranged so that the cutting edge of the blade travels at the speed of the moving rod.

The present invention consists of a mechanism for use in severing an axially moving rod into lengths wherein a flanged ledger plate having a radial slot is arranged in such a manner that the rim of the plate (which is adapted to travel at the axial speed of the rod) supports the rod during the major portion of the cutting operation and the final

cut of the rod is effected when the direction of the radial slot is normal to the direction of the axis of the moving rod.

Further the present invention consists of a mechanism for use in severing an axially moving rod into lengths which comprises a flanged ledger plate, rotatable in a vertical plane which extends substantially through the axis of the rod, and arranged so that the rim of the plate supports the moving rod and travels at the axial speed thereof, and a radial slot or slots cut in the rim and flange are arranged to receive periodically a cutting blade or blades to sever the rod into lengths.

The invention is more particularly described with reference to the accompanying drawings, in which:—

Fig. 1 illustrates in elevation a ledger plate constructed according to the present invention.

Fig. 2 is a plan view of Fig. 1, and

Fig. 3 is a side elevation of Fig. 1 indicating the manner in which the cutting blade engages with the ledger plate.

Referring to the drawings, a moving rod 1 is continuously fed through a tubular guide 2 to a rotatable flanged wheel or plane 3 adapted to rotate in a vertical plane in such a manner that the rim 4 engages with the movable rod 1 and supports the same at the junction between the tubular guide 2 and a corresponding tubular guide 5. The flanged wheel 3 is driven at a speed such that the peripheral speed of the rim 4 is equal to the axial speed of the rod 1. The flanged wheel 3 is provided with a flange 6 located on that side of the wheel towards which a rotatable cutting blade 7 moves in its circular path.

The flanged wheel 3 is provided with a series of radial slots 8 which are adapted to receive the cutting blade 7 and support the same against lateral displacement relatively to the wheel 3 during the cutting operation.

The rotary cutting blade 7 is arranged to engage with the slot 8 in the rim 4 and flange 6 of the wheel in such a manner that the action of the blade 7 forces the cigarette rod 1 into engagement with the rim 4 and thereby ensures during the major portion of the cutting operation the moving rod 1 and the

edge of the cutting blade are being carried by the ledger plate at a constant speed.

When the blade has passed sufficiently through the moving rod 1 to engage with the 5 flange 6, the ledger plate has been moved into a position in which the direction of the slot 8 in engagement with the blade is substantially normal to the axis of the moving rod, and thereby ensure that the remaining portion of 10 the cut is normal to the direction of the axis of the moving rod.

With a ledger plate of the above character, the tubular guides 2 and 5 through which the continuously moving rod 1 travels, extend 15 into close proximity with one another and the end face of one tube is shaped in such a manner that the cutting edge of the blade is in engagement therewith as the blade moves into engagement with the slot in the plate and the 20 face of the other tube is constructed so that the blade engages therewith during the final cutting operation.

Thus it will be seen that faces of the tube are constructed so as to assist the cutting 25 blade in its normal path through the moving rod and constitute a support which completely encircles the rod close up to the knife edge as the same severs the rod.

What I claim as my invention and desire 30 to secure by Letters Patent is:—

1. In mechanism for severing an axially moving rod into lengths, the combination with a rotatable cutting blade having a peripheral cutting edge of varying radius progressively increasing in the direction of cutting action, of a rotatable ledger plate having a circumferentially disposed flange extending parallel to the rotational axis of the 35 plate for supporting the rod, said flange being slotted to receive said blade during the cutting operation whereby the point of cutting action moves substantially parallel to the axis of said ledger plate.

2. In mechanism for severing an axially 45 moving rod into lengths, the combination with a rotatable cutting blade having a peripheral cutting edge of varying radius progressively increasing in the direction of cutting action, of a rotatable ledger plate 50 having a circumferentially disposed flange extending parallel to the rotational axis of the plate, said flange being slotted to receive said blade during the cutting operation, the axes of rotation of said blade and said plate being 55 transversely disposed whereby the point of cutting action moves substantially parallel to the axis of said ledger plate.

3. In mechanism for severing an axially 60 moving rod into lengths, the combination with a rotatable cutting blade having a peripheral cutting edge of varying radius progressively increasing in the direction of cutting action, of a rotatable ledger plate 65 having a flange extending radially of and a 70 flange extending substantially parallel to axis

of said plate for supporting said rod, said last named flange being slotted to receive said blade during the cutting operation whereby the point of cutting action moves substantially parallel to the axis of said ledger plate. 75

In testimony whereof I hereunto affix my signature.

WALTER EVERETT MOLINS.
